LLP(57) **CLAIM**The ornamental design for a sculpted impeller, as shown and
described.**DESCRIPTION**

FIG. 1 illustrates a perspective view of the design for the sculpted impeller, wherein the sculpted impeller includes a plurality of impeller blades each having a sculpted portion with a nonlinear profile extending between a shroud intersect surface at a shroud and a hub intersect surface at a hub. In this drawing, the solid lines illustrate the claimed ornamental design, whereas the broken lines illustrate environmental features that form no part of the claimed ornamental design of the subject embodiment.
